UNITED STATES PATENT OFFICE

HARRY L. TODD, OF LOS ANGELES, CALIFORNIA

DESIGN FOR A DESK PROTECTOR

Application filed June 17, 1929. Serial No. 31,727. Term of patent 14 years.

To all whom it may concern:

Be it known that I, HARRY L. TODD, a citizen of the United States, residing at Los Angeles, in the county of Los Angeles and State of California, have invented a new, original, and ornamental Design for Desk Protectors, of which the following is a specification, reference being had to the accompanying drawing, forming part thereof.

I claim:

The ornamental design for a desk protector, as shown.

In testimony whereof I affix my signature.

HARRY L. TODD.
